UNITED STATES PATENT OFFICE.

REUBEN D. TITTLE, OF SPRINGFIELD, OHIO.

WASHING MACHINE.

1,419,427.

Specification of Letters Patent. Patented June 13, 1922.

Application filed March 2, 1921. Serial No. 449,251.

To all whom it may concern:

Be it known that I, REUBEN D. TITTLE, a citizen of the United States, residing at Springfield, in the county of Clark and State 5 of Ohio, have invented certain new and useful Improvements in Washing Machines, of which the following is a specification, reference being had therein to the accompanying drawing.

10 This invention relates to washing machines.

In the ordinary washing machine the cleansing action is effected by causing the hot soapy water or suds to pass through the 15 clothes and it is customary to accomplish this either by forcing the clothes through the water, as by means of a dolly, or by imparting movement to the clothes receptacle in such a manner as to cause the water to move 20 from side to side thereof, thus forcing the same through the clothes.

One object of the present invention is to provide a washing machine having means for forcing the suds or hot water through 25 the clothes in a stationary receptacle.

A further object of the invention is to provide such a washing machine which will be simple in its construction and operation and which can be produced at a relatively 30 low cost.

Other objects will appear as the invention is described in detail.

In the accompanying drawings Fig. 1 is a side elevation of a washing machine embodying my invention, partly broken away; Fig. 2 is a top plan view, partly in section, of such a washing machine; Fig. 3 is a sectional view of a portion of the bottom of the machine; Fig. 4 is a detail view of a portion of the 40 operating mechanism; Fig. 5 is a vertical section of a portion of such a washing machine, taken through one of the cylinders; and Fig. 6 is a transverse section taken on the line 6—6 of the cylinder in Fig. 5.

45 In these drawings I have illustrated one embodiment of my invention and have shown the same as applied to a cylindrical clothes receptacle. It will be understood, however, that this particular embodiment of the invention has been chosen for the purpose of illustration only and that the invention may take various forms and may be applied to clothes receptacles of various kinds.

In that particular form of the invention 55 here shown the clothes receptacle 1 is shown

as a wooden tub having cylindrical side walls and a flat bottom 2, this tub being mounted upon any suitable support, such as legs 3. The tub or the receptacle is provided with a movable closure 4 to permit access to be 60 had thereto.

In order to cause the water in the receptacle to circulate through the clothes I have provided an apparatus for withdrawing portions of the water from the receptacle and 65 then discharging the same forcibly into the receptacle and through the clothes therein. This apparatus may take various forms and may be arranged in various positions with relation to the clothes receptacle, and in the 70 present construction I have shown a plurality of devices spaced about the walls of the receptacle and communicating therewith. As here shown, each device comprises a cylinder 5 communicating with the interior 75 of the clothes receptacle and having mounted therein a piston 6 by means of which the water may be drawn into the cylinder from the receptacle and then forced out of the receptacle through the clothes. Preferably the 80 cylinder communicates with the receptacle near the bottom thereof and, in the present instance, each cylinder is provided at its lower end with an inlet 7 which is controlled 85 by a flap valve 8. Further, each cylinder 85 is provided with a discharge opening 9 which may, if desired, include a nozzle 10, and as here shown the discharge opening is of a long, narrow construction and the nozzle is 90 so shaped as to spread the water as it is discharged into the receptacle. The discharge openings are arranged below the normal level of the water in the receptacle and where a plurality of devices are employed it is preferable that the discharge openings 95 for the several devices be arranged at different distances from the bottom of the receptacle so as to cause the water discharged into the receptacle to act upon all portions of the clothes therein. It is also desirable that a 100

screen of some sort be provided to prevent clothes within the receptacle from being drawn into the cylinder along with the water and in the present construction I have provided the receptacle with a secondary 105 perforated bottom 11 extending across the full width thereof, and have so arranged the cylinders that the inlet opening 7 is below the level of this secondary bottom or screen. Consequently, the water will be drawn down- 110

wardly through the clothes by the suction of the pistons in the cylinders and will then be discharged from the cylinders into the receptacle and through the clothes therein 5 above the secondary bottom or screen. This secondary bottom or screen may be of any suitable form but I have, in the present instance, shown the same as comprising a series of sections in the form of sectors which 10 are supported along their converging edges by flanges 12. This construction not only enables the screen to be easily placed in position or removed but it also provides adequate support for the intermediate portions 15 of the screen. I prefer that the cylinders 5 should be mounted permanently on the receptacle and where they are arranged within the receptacle, as here shown, the sections of the screen are provided with recesses to 20 receive the lower ends of the cylinders, the cylinder being provided with a flange 13 to receive and support the adjacent portion of the screen. The circumferential edges of the screen may be supported by a shoulder, 25 or block, 14, as shown in Fig. 3. The upper ends of the cylinders may, if desired, be provided with caps, or closures, 14 to prevent any water which may work its way past the pistons from splashing out of the upper ends 30 of the cylinders, such caps being provided with air ports 15.

The pistons may be operated by means of any suitable mechanism and, in the present construction, each piston has a piston rod 35 16 extending above the upper end of the cylinder and connected by an arm 17 with an actuating rod 18 which is slidably mounted in guides 20 secured to the receptacle 1. Rock arms 21 and 22 are pivotally mounted 40 between their ends beneath the receptacle, in intersecting lines, and are connected at their ends with the lower portions of the actuating rods 18, preferably by means of links 23, it being understood that each of 45 the rock arms is connected with two of the actuating rods. Rocking movement is imparted to the arms by means of a crank shaft 24 having two cranks which are connected by means of links 25 and 26 with the respective rock arms. Any suitable means may be 50 provided for rotating the crank shaft but in the present instance the apparatus is intended for operation by hand and I have mounted on the crank shaft, at the side of 55 the machine, a crank wheel 27 having a handle 28 by means of which it may be rotated. The operation of the apparatus will be readily understood from the foregoing description and it will be apparent that as the 60 crank wheel and crank shaft 24 are rotated the several pistons will be reciprocated in their cylinders, thus drawing into the cylinders the hot water from the receptacle and then forcibly discharging this water into the 65 receptacle and through the clothes. It will

further be apparent that the apparatus for accomplishing this may take various forms and may be mounted either inside or outside of the receptacle and may be actuated in any suitable manner either by power or by hand. 70 I, therefore, wish it to be understood that while I have shown and described one embodiment of my invention I do not wish to be limited to the details thereof as various modifications may occur to a person skilled 75 in the art.

Having now fully described my invention what I claim as new and desire to secure by Letters Patent is:

1. In a clothes washing machine, the combination with a clothes receptacle having a screen spaced a short distance above the bottom thereof, of a plurality of cylinders mounted on said receptacle and spaced one from the other about the vertical walls of 80 said receptacle, each of said cylinders having a valve controlled inlet communicating with said receptacle below said screen and having a lateral outlet opening directly into said receptacle above said screen and below the normal level of the water in said receptacle, pistons mounted in said cylinders above said outlets, and means for actuating said pistons to cause said water to be drawn downwardly 85 through the clothes and into said cylinders 90 upon the upward strokes of the pistons and to be forcibly discharged through said outlets and through the clothes in said receptacle upon the downward strokes of said pistons. 95

2. In a clothes washing machine, the combination with a clothes receptacle having a screen spaced a short distance above the bottom thereof, of a plurality of cylinders mounted on said receptacle and spaced one from the other about the vertical walls of 100 said receptacle, each of said cylinders having a valve controlled inlet communicating with said receptacle below said screen and having a lateral outlet opening directly into said receptacle above said screen and below the normal level of the water in said receptacle, pistons mounted in said cylinders above said outlets, and means for actuating said pistons to cause said water to be drawn downwardly 105 through the clothes and into said cylinders 110 upon the upward strokes of the pistons and to be forcibly discharged through said outlets and through the clothes in said receptacle upon the downward strokes of said pistons. 115

3. In a washing machine, the combination with a clothes receptacle having a screen spaced a short distance above the bottom thereof, a cylinder mounted on said receptacle, having a valve controlled inlet communicating with said receptacle below said screen, 120

125

and having a lateral outlet opening directly into said receptacle above said screen and below the normal level of the water in said receptacle, a solid piston mounted in 5 said cylinder above said outlet, and means for actuating said piston to cause water to be drawn downwardly through the clothes and into said cylinder upon the upwardly stroke of the piston and to be forcibly 10 charged through the outlet and through the clothes in said receptacle upon the downward stroke of said piston.

4. In a washing machine, the combination with a clothes receptacle, of a plurality of 15 cylinders spaced about said receptacle and each having a valve controlled inlet communicating with said receptacle and having a discharge opening arranged above said inlet, a piston mounted in each cylinder, a piston 20 rod connected with each piston and extending above the top of the respective cylinders, an actuating rod connected with each piston rod, rock arms mounted beneath said receptacle and connected with the respective 25 actuating rods, and means for imparting rocking movement to said rock arms.

5. In a washing machine, the combination with a clothes receptacle, of a plurality of cylinders spaced about said receptacle and 30 each having a valve controlled inlet communicating with said receptacle and having a discharge opening arranged above said inlet, a piston mounted in each cylinder, a piston rod connected with each piston and extending 35 above the top of the cylinder, an actuating rod connected with each piston rod, rock arms mounted beneath said receptacle and connected with the respective actuating rods, a crank shaft mounted beneath said recepta- 40 cle and operatively connected with said rock

arms, and means for rotating said crank shaft.

6. In a clothes washing machine, the combination with a clothes receptacle, of a plurality of cylinders spaced about said receptacle and each having a valve controlled inlet communicating with said receptacle and having a discharge opening arranged above said inlet, a piston mounted in each cylinder, piston rods connected with the respective 45 pistons and extending above the tops of the respective cylinders, a rock arm mounted beneath said receptacle, means for connecting said rock arm with said piston rods, and means for actuating said rock arm. 50

7. In a clothes washing machine, a clothes receptacle, a plurality of cylinders mounted on said receptacle, and spaced apart about the vertical wall thereof, and each having a valve controlled inlet communicating with the lower portion of said receptacle, and having a lateral outlet opening directly into the upper portion of said receptacle and below the normal level of the water therein, the outlets from the several cylinders being arranged at different heights from the bottom of said receptacle, a piston mounted in each cylinder, and means for actuating said pistons to cause water to be drawn downwardly through the clothes in said receptacle and into the respective cylinders upon the upward strokes of the pistons therein and to be forcibly discharged through the outlet opening and through the clothes in said receptacle upon the downward strokes of said pistons. 65

In testimony whereof, I affix my signature hereto.

REUBEN D. TITTLE.
